UNITED STATES PATENT OFFICE.

DANIEL C. WILGUS, OF SAN FRANCISCO, CALIFORNIA.

HYDROCARBON BURNER AND FURNACE.

SPECIFICATION forming part of Letters Patent No. 739,043, dated September 15, 1903.

Application filed August 14, 1902. Serial No. 119,651. (No model.)

To all whom it may concern:

Be it known that I, DANIEL C. WILGUS, a citizen of the United States, residing in the city and county of San Francisco, State of California, have invented an Improved Hydrocarbon Burner and Furnace; and I hereby declare the following to be a full, clear, and exact description of the same.

My invention relates to improvements in hydrocarbon-furnaces and burners for the same. Its general object is to render more practicable the use of oil fuel in conjunction with marine boilers.

Specifically its objects are, first, to provide a burner in which all tendency on the part of the burner to clog by reason of impurities in the oil may be obviated without shutting off the fire or removing the burner from the furnace; secondly, to so construct the front of the furnace that the heat is equably distributed over the entire area of the fire-box, while the engine-room will be kept comparatively cool.

It consists of the parts and the construction and combination of parts, as hereinafter set forth, having reference to the accompanying drawings, in which—

Figure 1 is a plan view, with partial section, of my invention. Fig. 2 is a sectional view of the furnace end of burner. Fig. 3 is a longitudinal section of a boiler-furnace, showing application of burner. Fig. 4 is an end view of boiler-furnace.

A A' represent two concentric pipes respectively conveying steam or air and oil and having separate respective feed-pipes 2 3, united by a by-pass 4. Respective valves 5 6 control the fluid-supply to pipes 2 3, and the oil-pipe 3 has a regulating-valve 7, by which the oil-feed between certain limits (corresponding to the difference in consumption when the engine is running at full speed and when running at low speed or between high and low boiler-pressure) may be varied without entirely shutting off the oil. The stem of valve 7 carries an arm or pointer 8, which is movable between the stop projections 9 on a plate 10, held in place by the bushing-nut 11. By loosening nut 11 the plate can be turned, so that the maximum and minimum oil-supply may be varied according as circumstances demand. The oil-pipe A' pro-

jects rearwardly beyond the surrounding steam or air pipe A and is slidable in a bushing 12 in the latter. A hollow plug 13 screws 55 into the front end of pipe A'. The outer end of the plug has an annular flange or baffle 14, while a portion intermediate of said baffle and the end of pipe A' is turned down to form an annular steam-passage and is provided 60 with studs 15, bearing against the inner wall of the reducer or perforated cap 16 on the end of the steam-pipe A, by which the concentric position of the oil-pipe and plug is maintained in relation to the steam-pipe and 65 the reducer. The space 17 between the baffle 14 and the end of the reducer or cap 16 forms an annular steam-outlet passage. A rod 18 extends entirely through pipe A' and is slidable in a bushing 19 in the rear end of 70 said pipe. A helical spring 20 surrounds the projecting portion of the rod and has one end bearing against the bushing and the other against an adjustable nut 21 on the rod. The opposite end of the rod carries a radially- 75 grooved flange or button 22 of approximately the same diameter as baffle 14. This button is adapted to bear against the outer concaved surface of the latter, and the radial grooves 23 form the oil-outlet passages. The 80 button is held to its seat by means of the spring 20.

In case the oil-passages become clogged by sand, strings, or other impurities ordinarily carried by the low-grade fuel-oils, these 85 passages can be cleared without removing the burner from the furnace and even without disturbing the oil-feed by simply pressing on the nut 21 to compress the spring 20 and open up a space between the end of button 90 22 and the end of plug 13 and allow the impurities to be washed out. This feature of a flushing means for the oil-passage is of great importance in operating burners, for frequently serious embarrassment is occasioned 95 by the burners becoming clogged and with no other way of overcoming the difficulty than to shut down the fires to enable a workman to get at the burner-tip. By turning the cock 4^a in the by-pass steam may be blown through 100 the oil-pipes to thoroughly cleanse them whenever necessary.

The pipe A' has a slight reciprocable movement in relation to pipe A for the purpose of

varying the size of outlet-passage 17, according to the supply of steam needed to volatilize the oil issuing through the groove-passages 23. This reciprocal movement is regulated by means of a coupling-ring 24, having a screw-threaded portion connecting with a rigid portion of the casing, as bushing 12, while the flange portion of the ring embraces a flanged sleeve 25, locked firmly on the oil-pipe A'. The ring is freely turnable about sleeve 25, but is prevented from lateral movement thereon by means of a ring 26.

The ring 24 is provided with a suitable handle 27, by which it can be easily turned to move the pipe A' and with it the plug 13 to enlarge or decrease the size of the steam-outlet passage 17. The length of pipes 23 is such that the latter will have a suitable spread to allow of this adjustment of pipe A' in pipe A. By commingling the steam and oil, as here shown, exterior to the burner-casing a small oil-pressure—say not to exceed four or five pounds—suffices. As the opening 17 is widened the flame will be in the form of a more and more contracted cone and will approach in appearance the straight-shot flame of an ordinary burner. As the opening is narrowed the flame will be more fan-like until it spreads in a circular sheet at right angles to the axis of the burner. This latter form of flame is particularly advantageous in marine boiler-furnaces of the corrugated type, where it is desired to have the heat as well toward the front of the fire-box as possible. In Figs. 3 and 4 I have shown this burner applied to such a furnace. B represents the fire-box. In lieu of the ordinary furnace-doors and draft means I brick up the front of the fire-box, as shown at 28, leaving the ventilating-pigeonholes 29 and the arch-passages 30, through which latter a man may enter the fire-box space, as for the purpose of inspecting the boilers. Extending out beyond the front of the furnace and practically continuous with the fire-box is a cylindrical sheet-metal shell 31, closed at the end and provided with a series of ventilators 32 upon its periphery, connected by suitable means, so as to be movable in unison. The wall 28 is suitably supported by means of the horizontal brackets 33, riveted or bolted to the cylinder-head, substantially as shown. In the bottom of the cylindrical extension is a manhole provided with a suitable closure, as 34. The ordinary iron furnace-front is disadvantageous where oil is used for many reasons. It does not retain the heat in the furnace, and the result is that in order to heat up the front of the fire-box properly the engine-room becomes unendurably hot. By disposing the brick wall 28 behind the burner the use of a fan-shaped flame is possible, whereby the heat will be deflected from the very first corrugation. The bricks becoming incandescent will assist to consume the oil and retain the heat products in the front of the furnace, while the air-jacket in the cylin-

drical extension will keep the engine-room comparatively cool. The pigeonholing 29 distributes the air equally to the flame, and 70 disposing the ventilators on the sides of the shell instead of in the end relieves the operator of the fierce glare of the furnace-fires.

Having thus described my invention, what I claim, and desire to secure by Letters Patent, is—

1. The combination in a hydrocarbon-burner, of a casing having separate oil and steam passages and separate oil and steam outlets; and a baffle over the end of the oil-passage and in contact with the end of the oil-pipe, and having radial outlets in its inner face, and a rearwardly-extending push-rod for lifting the baffle from the end of the oil-pipe and uncovering the oil-passage. 85

2. The combination in a hydrocarbon-burner, of a casing having separate oil and steam passages and independent outlets therefor; oil and steam pipes and a connecting valve-controlled by-pass; a baffle normally seated against the end of the oil-pipe and having lateral outlets for the discharge of oil, said baffle having a stem extending rearwardly and adapted to be moved longitudinally to cause the baffle to uncover the end 95 of the oil-pipe; and a regulating-valve in the oil-pipe and removed from the oil-passages in the casing.

3. The combination in a hydrocarbon-burner, of a casing having separate oil and steam passages and independent outlets therefor; oil and steam pipes connecting with the said passages and a regulating-valve in the oil-pipe at a point removed from the oil-passage in the casing; a baffle seated against the 105 outlet end of the oil-passage and having lateral grooves forming outlets for the oil; a stem extending from the baffle and mounted to slide longitudinally in the casing; and a spring acting upon the stem to hold the baffle 110 normally in contact with the end of the oil-pipe said baffle uncovering said pipe when the stem is moved against the closing pressure of its spring.

4. The combination in an oil-burner of a 115 casing; steam and oil pipes; a by-pass connecting the same; and a baffle seating against the discharge end of the oil-pipe and having radial grooves forming a normal oil-discharge, said baffle having a push - stem slidably 120 mounted in the casing and capable of longitudinal movement to uncover the oil-pipe, and a spring again seating the baffle when the pressure upon the stem is released.

5. The combination in a hydrocarbon- 125 burner, of concentric oil and steam pipes, a perforated plug in the end of the inner pipe, an annular flange or baffle on the end of the plug, a normally-retracted push-rod extending centrally through said inner pipe and 130 plug and out of contact therewith, an enlargement on the end of said rod normally in contact with the outer surface of said plug and radially grooved to form an annular fluid-

discharge passage therewith, and means by which said enlargement is normally held in contact with said plug.

6. The combination in a hydrocarbon-burner, of concentric oil and steam pipes, said oil-pipe extending rearwardly beyond the steam-pipe and having a sliding movement within the latter, a perforated plug on the burner end of the oil-pipe, a perforated cap on the end of the steam-pipe said cap and plug forming the walls of the steam-discharge outlet, means by which the sliding movement of the one pipe within the other may be regulated to vary the size of said outlet, a normally-retracted spring-pressed rod extending centrally through the inner oil-pipe and means in connection with said rod coöperating with the end of said plug to form an oil-discharge outlet and means for reciprocating said rod.

7. The combination in a hydrocarbon-burner, of respective inner and outer concentric oil and steam pipes, a perforated plug in the end of said oil-pipe, a flange or baffle on said plug, a perforated cap on the end of the steam-pipe, means for longitudinally adjusting the plug to open or close the space between the end of the cap and the baffle, a normally retracted spring-pressed rod extending centrally through said pipe and plug, an enlargement on the end of the rod and adapted to form an oil-outlet with the outer face of the baffle, and means for moving said rod longitudinally against the pressure of its spring, to open said oil-outlet to allow the oil-passage to be flushed of impurities.

8. The combination in an oil-burner, of con-

centric oil and steam pipes, a perforated plug in the end of the oil-pipe, a perforated cap on the end of the steam-pipe embracing said plug, a flange or baffle on the end of the latter, the space between said baffle and the end of the cap forming a steam-outlet passage, said baffle and cap adjustable in relation to each other to vary the size of said outlet-passage, a spring-pressed rod extending through said oil-pipe and reciprocable therein, and means upon the end of said rod forming with the outer surface of said baffle the walls of the oil-outlet passage.

9. The combination in a hydrocarbon-furnace of a wall disposed in the front of the fire-box immediately behind the burner and provided with air-passages, an extension to said fire-box beyond the front wall of the furnace and forming an air-jacket, means carried by said extension for supporting said wall and ventilating means in said extension.

10. The combination in a hydrocarbon-furnace of a heat-non-conducting arch disposed in the front of the fire-box behind the burner, an extension beyond the furnace-front in continuation of said fire-box, said extension closed at the end, support means for said arch, ventilators in the sides of said extension and a manhole in the extension adjacent to the space beneath said arch.

In witness whereof I have hereunto set my hand.
